Primary Examiner — Susan Bennett Hattan*Assistant Examiner* — Marie Fast Horse(74) *Attorney, Agent, or Firm* — Abelman, Frayne & Schwab(57) **CLAIM**

The ornamental design for a money counter, as shown and described.

DESCRIPTION

FIG. 1 is a front, top, and right side perspective view of a money counter showing the new design; FIG. 2 is a top plan view thereof;

FIG. 3 is a front elevation view thereof;

FIG. 4 is a left elevation view thereof, the right elevation being a mirrored image thereof; and,

FIG. 5 is a rear elevation view thereof.

The broken lines in the drawings depict portions of the money counter that form no part of the claimed design.
